(57) **CLAIM**

The ornamental design for a hand dryer, as shown and described.

DESCRIPTION

FIG. 1 is a perspective view of a hand dryer according to the present invention;

FIG. 2 is a front elevation view of the hand dryer embodiment of FIG. 1;

FIG. 3 is a back elevation view of the hand dryer embodiment of FIG. 1;

FIG. 4 is a left elevation view of the hand dryer embodiment of FIG. 1;

FIG. 5 is a right elevation view of the hand dryer embodiment of FIG. 1;

FIG. 6 is a top plan view of the hand dryer embodiment of FIG. 1; and,

FIG. 7 is a bottom plan view of the hand dryer embodiment of FIG. 1.

The evenly spaced broken lines in the drawings show portions of the hand dryer, which form no part of the claimed design. The dash-dot broken lines define the bounds of the claimed design and form no part thereof.

1 Claim, 5 Drawing Sheets
